(57) CLAIM

The ornamental design for a jewelry and accessory organizer, as shown and described.

DESCRIPTION

FIG. 1 is a front elevation view of the jewelry and accessory organizer showing my new design;

FIG. 2 is a right side elevation view of the invention thereof;

FIG. 3 is a top view thereof;

FIG. 4 is a left side elevation view thereof; and

FIG. 5 is a rear elevation view thereof; and,

FIG. 6 is a bottom view thereof.

The broken lines are for environmental purposes only and form no part of the claimed design.
